UNITED STATES PATENT OFFICE

2,522,158

POSTER PANEL

Alexander L. Bauers and Max Rosner, Chicago,
Ill., assignors to General Outdoor Advertising
Co., Inc., a corporation of New Jersey

Application November 22, 1944, Serial No. 564,651

4 Claims. (Cl. 40—125)

1

This invention relates to an advertising display structure or poster panel, commonly called a billboard, and has for its object the provision of an advertising display structure in which the display panel may be shifted about pivots on the poster panel frame for the purpose of replacing the poster thereon.

A further object of the invention is to provide a poster panel with a panel thereon which may be easily and simply constructed and which may, without the use of any special tools or equipment, be shifted into an accessible position substantially in the plane of the poster panel to facilitate the replacement of the poster upon the poster panel.

Another object of the invention is to provide a poster panel upon which the removable display panel may be swung from display position into servicing position without requiring any substantial clearance about the poster panel.

Still another object of the invention is to provide a poster panel in which the removable display panel cannot only be lowered from its display position to a servicing position convenient to the ground, but in which the display panel itself may be detached from the frame on which it is supported and carried away from the poster panel for servicing or for replacement.

The display panel mounted upon a poster panel is designed to display an advertisement or poster when in the display position adjacent the poster panel. The display material exposed upon the display panel is usually temporary in character and is replaced either by painting the desired display upon the display panel or securing to it, by means of adhesive or other means of attachment, printed or lithographed advertising material. Occasionally three-dimensional displays are mounted upon the display panel.

In order to paint the display panel or to apply prepared posters or other displays thereto, some scaffolding or other means of access was necessary in order to reach the display panel while it remained in the display position as the display panel was conventionally an integral and stationary part of the poster panel structure and mounted at some height above the ground in order to display the display panel most advantageously.

Both because of the size of the display panels and the large posters used thereon, the problem of applying the posters or other displays to the display panel while in display position was accompanied with considerable difficulty. Even with the use of scaffolding and long handled brushes, the problem was one of some difficulty because of the lack of accessibility of the display panel.

Similarly, when either paint or adhesive was applied to the display panel, the splashing of the paint or adhesive smeared and disfigured the border of the display panel. Another problem that frequently arose in the use of display panels of this character because of the limited space in

2

which the poster panel was mounted or the lack of license to approach the panel except in its immediate vicinity was that the poster panel was not readily accessible to the use of long handled brushes and the lack of space forbade the use of scaffolding for servicing the display.

With the poster panel of this invention, the display panel can be easily swung from its display position to its servicing position and the operator 10 can then stand conveniently close to the display panel and reach its entire area for removal of the discarded display and its replacement by means of a new poster. When the display panel is swung into the servicing position, practically all of its 15 area is within reach of the attendant.

When the display panel is brought into its servicing position, not only is the work upon the display panel facilitated but the danger of splashing adhesive or paint upon the border of the 20 poster panel is obviated. This enables the display panel to be repeatedly recovered with new displays without requiring the simultaneous renewal or refinishing of the border.

These and other features of the invention will 25 be seen from the following detailed specification read in connection with the accompanying drawings forming part thereof and in which—

Fig. 1 is a front elevation of a poster panel with the display panel in display position and the 30 operating mechanism disclosed in broken lines;

Fig. 2 is a front elevation of the poster panel shown in Fig. 1 with the poster panel swung into servicing position;

Fig. 3 is a rear elevation of the poster panel 35 showing the framework and operating mechanism;

Fig. 4 is a section taken on the line 4—4 of Fig. 3 of the poster panel of this invention;

Fig. 5 is a section of the poster panel of this 40 invention taken on the line 5—5 of Fig. 3.

Referring to the drawings the poster panel 11 is of conventional construction attached to the side or top of a building or supported on the ground by suitable supports (not shown). The 45 poster panel is formed of the border 12 which may be suitably flanged by the turned in flange 13 about the border. Within the border 12 is the display panel 15 upon which a poster bearing an advertising display or message is applied by means of suitable adhesives or other attaching means.

The display panel 15 has suitable frame members shown in the illustrative representation herein as the vertical members 16 secured to the display panel. The poster panel framework includes suitable frame members such as the vertical beams 17 joined to horizontal beams 18. The arrangement, size and number of these frame members may be widely varied according to conventional structural practice. The display 55 panel 15 is pivotally mounted upon the poster panel frame by means of the pivoted arms 19 which swing on the stationary pivots 20, as best

shown in comparison of the structures of Figs. 1 and 2. The stationary pivots are perpendicular to the plane of the poster panel so that the arms 19 swing in a plane parallel to the plane of the poster panel.

Suitable counterweights 21 may be mounted upon the free ends of the framework of the display panel to facilitate the movement of the display panel. Secured to the frame upon which the display panel moves is the handle 22 which may be reached through an access door 14 in the border 12 of the poster panel. This access door 14 is not necessary except where the poster panel is secured to the wall of a building or is otherwise so mounted that access to the rear of the poster panel is difficult.

In the preferred embodiment of the invention shown in the accompanying drawings, the display panel 15 is shown as constructed upon the vertical frame members 16 which are in turn pivoted to the pivoted arms 19 by means of the bolts 24 which are also perpendicular to the plane of the poster panel. These bolts may be made so they are readily removable to enable the display panel 15 with the vertical support 16 to be detached from the pivoted arms 19 and the display panel removed from the poster panel structure. This is particularly important where it is desired to carry the display panel away from its location for servicing or the replacement of the display thereon.

In order to protect the display panel against unnecessary flow of water from the border 12 thereover, the border of the poster panel may be fitted with the eave 23 which may be provided as shown in Fig. 5 to protect the display panel.

Obviously, the proportions and dimensions of the various structural elements and the location and size and weights of the counterweights can be modified over a wide range and the number and location of the pivoted arm members shown in the several modifications of the invention may be varied in number, size and form.

Method of operation

In order to service the display panel 15 it is only necessary to swing the display panel upon its pivoted arms 19 from its display position within the border 12 of the poster panel structure into the servicing position shown in Fig. 2 when the display panel is brought beneath the poster panel structure but in substantially the same plane as it occupied when in display position.

In the servicing position the entire area of the display panel 15 is readily accessible to the operator and the possibility of soiling or defacing the border 12 is greatly reduced by virtue of the fact that the display panel 15 stands in front of the lower portion of the border 12 and protects it against dripping adhesives or paint.

If desired the display panel 15 may be unbolted from the pivoted arms 19 while the display panel is in servicing position and the display panel then removed from the location of the display to a shop for painting or other servicing. Obviously, if the display panel is to be unbolted from the pivoted arms 19 some means (not shown) must be employed to lock the counterweights in their upper position while the display panel is disconnected from the pivoted arms 19.

When the servicing of the display panel 15 has been attended to, the panel may be readily swung back from its servicing position into its display position where it will be held by the counter-

weights or, if desired, by suitable locking means (not shown).

In moving the display panel the handle 22 may be reached through the access door and employed to move the panel.

Having thus shown and described one embodiment of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

What is claimed is:

1. A poster panel comprising a stationary border, a plurality of braces carried by the border and extending within the confines of the border, a display panel, and a plurality of arms pivoted to the braces within the confines of the border to be swung in a plane parallel to the plane of the display panel and pivoted to the display panel for supporting the display panel immediately in front of the border in display position and for swinging the display panel in its own plane from the display position to a servicing position below the display position.
2. A poster panel comprising a stationary border, a plurality of braces carried by the border and extending within the confines of the border, a display panel, a plurality of arms pivoted to the braces within the confines of the border to be swung in a plane parallel to the plane of the display panel and pivoted to the display panel for supporting the display panel immediately in front of the border in display position and for swinging the display panel in its own plane from the display position to a servicing position below the display position, extensions on the pivoted arms, and counterweight means carried thereby.
3. A poster panel comprising a stationary border frame including a border, a display panel and linkage swingable in a plane parallel to the display panel and pivoted to the border frame and the display panel on parallel axes perpendicular to the display panel for supporting the display panel immediately in front of the border in display position and for swinging the display panel in its own plane from the display position to a servicing position below the display position.
4. A poster panel comprising a stationary border frame including a border, a display panel, linkage swingable in a plane parallel to the display panel and pivoted to the border frame and the display panel on parallel axis perpendicular to the display panel for supporting the display panel immediately in front of the border in display position and for swinging the display panel in its own plane from the display position to a servicing position below the display position and counterweight means carried by the linkage.

ALEXANDER L. BAUERS.
MAX ROSNER.
